UNITED STATES PATENT OFFICE

FRANK J. LASAR, OF SAN FRANCISCO, CALIFORNIA, ASSIGNOR TO CHAMPION WASHER COMPANY, LTD., A CORPORATION OF NEVADA

WASHING MACHINE

Application filed May 21, 1927. Serial No. 193,241.

My invention relates to improvements in washing machine construction wherein actuating mechanism is mounted within and upon a housing bracket secured upon a wall above a stationary wash tray and arranged to reciprocate an agitating element within the tray.

The primary object of the present invention is to provide an improved washing machine construction whereby an agitating element may be efficiently operated directly in a wash tray.

Another object is to provide an improved means for mounting actuating mechanism within a housing bracket to afford increased strength and rigidity, and to render the machine more durable and efficient.

A further object is to provide an improved actuating mechanism adapted to permit an efficient operation of the machine at increased speed.

A still further object is to provide an improved machine in which the actuating gears may be caused to run in grease without danger of permitting grease to leak into the tray of materials being washed.

I accomplish these and other objects by means of the improved device disclosed in the drawings forming a part of the present application wherein like characters of reference are used to designate similar parts throughout the specification and drawings, and in which,

Fig. 1 is a front elevation of my improved washing machine,

Fig. 2 is a rear elevation of the machine, and

Fig. 3 is a vertical section of the machine.

Referring to the drawings, the numeral 1 is used to designate in general a housing bracket, the upper portion of which is substantially circular and provided with a flange 2 whereby the bracket may be secured directly upon the wall or other supporting structure directly over an ordinary wash tray 3. The bracket is provided with a downwardly disposed extension 4 having a slot 6 in the front thereof. A pair of guides 7 are mounted within the bracket extension 4 upon op-

posite sides of the slot 6 to receive a cross-head 8 slidably mounted thereon and having an arm 9 extending outwardly through the slot in the front of the bracket. An agitating element comprising a plurality of suction cups 11 mounted upon a common stem 12 by means of a vane plate 13 is detachably and adjustably secured upon the arm 9, said agitating element being arranged to be reciprocated within the tray 3 by means of the cross-head 8.

A shelf 14 is formed integrally with the housing bracket 1 to form a support for a motor 16 secured thereon and controlled by a suitable two way switch 17 electrically connected in the well known manner between the motor and a source of electrical energy, not shown.

A gear box 18 comprising a body provided with lugs 19 formed around the edges flush with one face thereof is secured against the inner surface of the front of the housing bracket 1 by suitable securing members 21. A drive shaft 22 is journaled within the upper portion of the box 18, said shaft being supported within enlarged bearing blocks formed within the upper corners of the box and extending outwardly through one side of the box. A flexible coupling 23 is connected between the shaft and the motor shaft through an opening formed in the side of the housing bracket.

A worm 24 is mounted upon the shaft 22 and arranged in meshing relation with a worm gear 26 mounted upon a worm gear shaft 27 journaled upon the box 18, the forward end of the shaft 27 extending through the front of the box 18 and the housing bracket 1 while the rearward end of the shaft 27 extends outwardly through a cover plate 28 closing the back of the box 18. A crank 29 is mounted upon the rearward end of the shaft 27 outside of the box, and a connecting rod 31 is connected between the crank and the cross-head 8.

The gear box 18 is constructed and the gears and shafts assembled therein entirely independently of the housing bracket 1, the box being packed with grease before the cover

plate 28 is secured in place upon the back of the box. The lugs 19 are distributed around the edge of the box so that the load is distributed over a large area of the bracket, whereby the box, which is preferably made of cast iron, may be rigidly supported upon the bracket, which is made of cast aluminum, without imposing undue strain upon any portion of the bracket or the securing members. 5 This feature is of primary importance in the present invention as the shafts 22 and 23 may be efficiently journalled upon the hard metal gear box and may be operated efficiently at high speed without appreciable wear. In this 10 respect, the present invention is a material improvement over washing machine constructions of the present type, wherein the shafts are journalled directly in the aluminum mounting bracket and the strain and 15 wear is so great that the machine can be operated only at low speed, and wear and distortion is so great that the machine is of relatively short life. Furthermore, my improved construction permits the gears to run in 20 grease or oil at all times, thereby obtaining a noiseless operation free from wear without permitting any possible leakage of oil or grease into the wash tray. When once assembled, the gear box and gears will insure 25 an efficient operation indefinitely without further care or attention.

In operation, the motor is driven to rotate the crank arm 29 and thereby reciprocate the cross-head 8 and the agitating element 35 in the obvious manner. The rigid mounting obtained insures a quiet and efficient operation substantially free from vibration, and permits the agitating element to be operated at a relatively high speed whereby a rapid 40 and efficient washing of clothes or other materials may be effected.

A wringer 32 is mounted upon an arm 33 formed upon the bracket 1 and extending to a point above the edge of the tray. The 45 wringer is driven by a chain 34 mounted over a sprocket 36 carried by the wringer and a sprocket 37 loosely mounted upon the outer end of the shaft 27. A suitable clutch member 38, operable from the front of the bracket 50 1, is arranged to cause the sprocket 37 to be engaged or disengaged from the shaft 27 for connecting or disconnecting the wringer drive as desired.

Applicant is aware that washing machines 55 of the general type illustrated and described are known in the art, and he therefore does not claim as his invention the general principle and arrangement of the washing machine as disclosed, but claims only the specific details of construction and such modifications thereof as may fall within the scope 60 of the appended claim.

Having thus described my invention what I claim as new and desire to secure by Letters 65 Patent is:

A drive mechanism for washing machines comprising a mounting bracket formed from light, soft metal; an independently constructed gear box formed from relatively heavy, rigid metal mounted within the mounting 70 bracket and secured upon the inner surface thereof at a plurality of spaced points to distribute the strain thereon over a large area; a power driven shaft journalled within the gear box and extending outwardly through 75 one side of said box and the bracket for connection to a source of power; a worm secured upon said shaft; a second shaft journalled within the gear box; a worm gear mounted upon said second shaft in meshing relation 80 with the worm; and means connected to the second shaft for actuating washing mechanism.

In witness whereof I hereunto set my signature.
